Lewis O. Hitchman
ATTORNEY

UNITED STATES PATENT OFFICE.

CARL G. SWEBILIUS, OF NEW HAVEN, CONNECTICUT, ASSIGNOR TO THE MARLIN FIREARMS CORPORATION, OF NEW HAVEN, CONNECTICUT, A CORPORATION OF DELAWARE.

FIREARM.

Application filed December 3, 1921, Serial No. 519,643. Renewed November 17, 1925.

To all whom it may concern:

Be it known that I, CARL GUSTAF SWEBILIUS, a citizen of the United States, residing at New Haven, in the county of New Haven and State of Connecticut, have invented certain new and useful Improvements in Firearms, of which the following is a full, clear, concise, and exact description.

This invention relates to firearms and 10 more especially to sporting rifles of the single shot type.

In rifles of the single shot type now on the market, it is necessary, when loading, to manually partially chamber the cartridge by 15 pushing the nose thereof into the bore of the barrel a sufficient distance so that the cartridge is in axial alignment with the barrel to allow the breech bolt, when closing, to thrust the cartridge the rest of the way 20 into the barrel without jamming.

It is the object of this invention to render unnecessary the manual positioning of the cartridge in the barrel, when loading a gun of this type. This object is accomplished by providing means within the receiver of the gun for automatically positioning a cartridge in axial alignment with the bore of the barrel. The breech bolt on closing thrusts the cartridge the whole distance 30 into the barrel. The cartridge may thus be merely dropped through the loading opening into the receiver and will be chambered without being touched further by the operator of the gun.

Further objects and advantages of this invention will be apparent from the following specification and accompanying drawing wherein Fig. 1 is a side elevation of a gun embodying the invention with the breech 35 open; Fig. 2 is a similar view of the receiver with the side plate removed; Fig. 3 is a view similar to Fig. 2 with the breech closed and Fig. 4 is a plan view of the receiver with the top wall broken away.

Referring now to the drawing 10 is the receiver, 11 the stock, and 12 the barrel. A breech bolt 13 is reciprocally mounted in the receiver and when in its forward position completely closes a slot in the right hand wall of the receiver formed between the top of the receiver and the removable side plate 14. A locking lever 15 is pivotally mounted on the breech bolt 13 and abuts against the stop 16 to lock the breech

bolt in its forward position. Extending at 55 right angles from the main portion of the locking lever is a lug 17 on which is provided a stud 18. Extending from the front wall of the receiver is a rod 19 upon which is reciprocably mounted the handle 20. The 60 action slide 21 is attached at its front end to the handle 20 and is provided at its rear end with an aperture in which is received the stud 18. The hammer 22 is pivoted to the side wall of the receiver and extends 65 through a slot in the top wall to the rear of and in alignment with the breech bolt. A trigger 23 is pivotally mounted in the bottom wall of the receiver and cooperates with the hammer to hold the latter in cocked position. Reciprocation of the handle 20 is effective to move the breech bolt to open and 70 close the breech and to set the hammer in cocked position.

A cartridge support 24 is mounted on a 75 stud 25 carried by the side wall of the receiver slightly below the bottom of the breech bolt and at a point slightly in advance of the front end of the breech bolt when it is in its rearmost position. The 80 support extends forward nearly to the front wall of the receiver and is provided at its rear edge with an upper extending lip 26 to position the cartridge laterally of the receiver. A spring 27 tends to move the front end of the support to the position shown in 85 Figs. 1 and 2 and a pin 28 carried by the support and working in a groove in the side wall limits the pivotal movement of the support. When the breech bolt is in its rear 90 position, the spring holds the forward end of the cartridge support in its upper position but as the breech bolt moves forward it depresses the support to a position where a cartridge carried by the support is in alignment 95 with the barrel and is in proper position to be chambered by the closing of the breech. A leaf spring 29 is attached at one of its ends to the upper wall of the receiver and extends toward the front wall of the receiver. The forward end of the spring is turned down slightly and terminates adjacent the rim of the cartridge chamber.

To load the gun it is necessary only to pull back on the handle 20 to move the breech bolt to the rear and open the slot in the receiver. The cartridge support then assumes the position shown in Figs. 1 and

2. A cartridge is then slipped through the slot in front of the breach bolt onto the support 24, said slot being the only place through which a cartridge can be inserted into the gun. The cartridge assumes a tilted position relative to the barrel because of the fact that the forward end of the support is in its upper position and the position of the cartridge laterally of the receiver is determined by the lip 26. The handle 20 is then moved forward and the breech closed. When the breach bolt engages the upper surface of the support 24 the front end of the support is moved down to its normal position bringing the cartridge into alignment with the bore of the barrel. The spring 29 cooperates in this operation by directing the nose of the cartridge into the chamber. The bolt then pushes the cartridge forward and chambers it. The cartridge is thus automatically chambered and it is unnecessary to manually direct the cartridge into the chamber.

It is to be understood that various modifications may be made in this device without in any way departing from the spirit of the invention as set forth in the following claims.

What is claimed is:

1. In a gun, a receiver having a slot, a reciprocable breech bolt therein, movable means to support a cartridge inserted through said slot in position to be chambered by said breech bolt, and a spring in said receiver adapted to be engaged by a cartridge on said supporting means.

2. In a gun, a receiver having a slot, a breech bolt reciprocatively mounted therein, a movable member to receive a cartridge inserted through said slot and locate it in position to be chambered by said breech bolt, and a spring in said receiver adapted to engage a cartridge on said member.

3. In a gun, a receiver having a slot in its side wall, a breech bolt reciprocatively mounted in said receiver in alignment with said slot, a member pivotally mounted below the path of said bolt, and means to rotate said member into the path of said bolt, said member being adapted to receive a cartridge inserted through said slot and locate it in position to be chambered by said bolt.

4. In a gun, a receiver having a slot in its side wall, a breech bolt reciprocatively mounted in said receiver in alignment with said slot, a member pivotally mounted in said receiver below the path of said breech bolt and adapted to be rotated in one direction by said breech bolt and means to rotate said member in the opposite direction, said member being adapted to receive a cartridge inserted through said slot and locate it in position to be chambered by said bolt.

5. In a gun, a receiver having a slot, a breech bolt movably mounted in said receiver and closing said slot, a movable member to

receive a cartridge inserted through said slot and locate it in position to be chambered by said breech bolt, the movement of said member being controlled by said breech bolt, and a spring in said receiver to engage a cartridge on said member.

6. In a gun, a receiver having a slot, a reciprocable breech bolt closing said slot, and a pivoted member to receive a cartridge inserted through said slot and locate it in position to be chambered by said breech bolt, the movement of said pivoted member being controlled by said breech bolt, and a spring in said receiver to engage a cartridge on said member.

7. In a gun, a receiver having a slot in its side wall, a reciprocable breech bolt closing said slot, a member pivoted below the path of said breech bolt to receive a cartridge inserted through said slot and locate it in position to be chambered by said breech bolt and means to rotate said member in one direction, said bolt being adapted to engage said member to rotate it in the opposite direction.

8. In a gun, a receiver having a slot, said slot providing the sole means for inserting a cartridge into said receiver, a breech bolt movably mounted in said receiver, means to receive a cartridge inserted through said slot and locate it in position to be chambered by said breech bolt, and a spring in said receiver to engage a cartridge on said member.

9. In a gun, a receiver having a slot in its side wall, said slot providing the sole means for inserting a cartridge into said receiver, a breech bolt movably mounted in said receiver and closing said slot and a movable member below the path of said breech bolt to receive a cartridge inserted through said slot and locate it in position to be chambered by said breech bolt, the movement of said member being controlled by said breech bolt.

10. In a gun, a receiver having a slot in its side wall, said slot providing the sole means for inserting a cartridge into said receiver, a breech bolt reciprocatively mounted in said receiver and closing said slot, a member pivoted in said receiver below said slot to receive a cartridge inserted through said slot, and means to rotate said member into the path of said breech bolt.

11. In a gun, a receiver having a slot, said slot providing the sole means for inserting a cartridge into said receiver, a slidable handle, a movable breech bolt closing said slot, movable means to receive a cartridge inserted through said slot and locate it in position to be chambered by said breech bolt, a spring to engage a cartridge on said means, and connecting means between said breech bolt and said handle.

12. In a gun, a receiver having a slot, said slot providing the sole means for inserting

- a cartridge into said receiver, a slidable handle, a reciprocable breech bolt closing said slot, movable means to receive a cartridge inserted through said slot and locate it in position to be chambered by said breech bolt, a spring to engage a cartridge on said means, and connecting means between said breech bolt and said handle. 5
13. In a gun, a receiver having a slot, said slot providing the sole means for inserting a cartridge into said receiver, a slidable handle, a reciprocable breech bolt closing said slot, a movable member to receive a cartridge inserted through said slot and locate it in 10 position to be chambered by said breech bolt, a spring to engage a cartridge on said member the movement of said member being controlled by said breech bolt, and connecting means between said handle and said breech bolt. 15
14. In a gun, a receiver having a slot in
- its side wall, said slot providing the sole means for inserting a cartridge into said receiver, a slidable handle, a reciprocable breech bolt closing said slot, a member below said slot for receiving a cartridge inserted through said slot, means to rotate said member into the path of said breech bolt, and connecting means between said breech bolt and said handle. 20
15. In a gun, a receiver having a slot, a breech bolt movably mounted in said receiver and closing said slot, a movable member to receive a cartridge inserted through said slot and a resilient member in said receiver to cooperate with said member to locate a cartridge in position to be chambered by said breech bolt. 25

In witness whereof, I hereunto subscribe my name this 11th day of November, A. D. 40 1921.

CARL G. SWEBILIUS.
